UNITED STATES PATENT OFFICE.

HIRAM HARRY HIRSCH, OF PHILADELPHIA, PENNSYLVANIA.

PORTABLE ELECTRIC-LIGHTING APPARATUS.

1,121,249.

Specification of Letters Patent. Patented Dec. 15, 1914.

Application filed March 3, 1913. Serial No. 751,837.

To all whom it may concern:

Be it known that I, HIRAM H. HIRSCH, a citizen of the United States, residing at Philadelphia, in the State of Pennsylvania, have invented a certain new and useful Improvement in Portable Electric-Lighting Apparatus, whereof the following is a specification, reference being had to the accompanying drawing.

- 10 My invention relates to apparatus including an incandescent lamp in co-operative relation with a storage battery provided with means to attach it to the person of a miner or other operator, and provides a safety casing for the lamp designed to extinguish the light to prevent ignition of fire-damp or other explosive gases when said casing is subjected to stresses tending to break the lamp.
- 20 As hereinafter described my invention includes a lamp casing and removable cover provided with a transparent lens or panel, normally assembled in substantially hermetical relation; said casing having distinct oppositely polarized elements included in the lamp circuit, so constructed and arranged that they are shifted to modify the lamp circuit and instantaneously extinguish the lamp, whenever said casing is crushed or
- 30 punctured.

My invention includes the various novel features of construction and arrangement hereinafter more definitely specified.

In the drawings:—Figure I is a vertical sectional view of a lamp casing conveniently embodying my invention and indicating its operative connection with a storage battery. Fig. II is a fragmentary front view of said casing with the cover removed. Fig. III is a fragmentary sectional view similar to Fig. I but showing the casing elements short circuited by crushing the casing. Fig. IV is a fragmentary sectional view similar to Fig. I but showing the casing elements shifted to break the lamp circuit by removal of the transparent panel. Figs. V and VI are fragmentary sectional views of a modified form of my invention, including elements adapted to short circuit the lamp when the casing is punctured, said views showing said casing respectively in normal and short circuited condition.

Referring to the form of my invention shown in Figs. I to IV inclusive; the lamp casing includes the outer metallic casing or shell 1 having the screw thread 2 to detach-

ably engage the cover 3, and having the socket of insulating material 4 supporting the inner metallic casing or shell 5 provided with the screw thread 6 to receive the incandescent electric lamp 7; said shell 5 serving as a reflector for the latter. Said shell 5 makes electrical contact with the metallic sleeve terminal 8 of said lamp which has the other metallic terminal 9 in electrical contact with the socket terminal 10. Said inner shell 5 is insulated from the outer shell 1 by the annular bands 11 and 12, the latter extending between the shoulders 13 and 14 respectively upon said inner and outer shells and bracing them in spaced relation; the outer edges of said casing shells 1 and 5 and insulating band 11 forming a seat for the gasket 16 which is preferably of resilient material, so that the transparent lens or panel 18 is secured in substantially hermetically sealed relation with said casing when the latter is assembled as indicated in Fig. I. As indicated, said outer shell 1 and inner shell 5 are oppositely electrically polarized by suitable connection with the storage battery 19, and said socket 4 also supports the spring 20, which extends between said outer shell 1 and inner shell 5; is normally in electrical contact with said outer shell 1 at 22, and has its free end projecting through the notch 21 in said inner shell so that it is normally upheld from the latter by the transparent panel 23, formed of glass or other frangible material. Said shell 5 is held in said socket 4 and electrically connected by the screw 24 which is insulated from the springs 10 and 20. It is to be understood that both the metallic and transparent elements of said casing are crushable so that when either is crushed the electric circuit is modified to extinguish the lamp 7 before it is possible for any incandescent portion thereof to ignite fire-damp or other ignitable gases from the atmosphere surrounding said casing. For instance, as shown in Fig. III the outer shell 1 has been crushed and displaced toward the inner shell 5 so as to bring the spring 20 into electrical contact therewith and thus close the circuit, including the battery 19, aside from the lamp and thus short circuit and extinguish the latter. As indicated in Fig. IV the panels 18 and 23 have been crushed and displaced so as to permit said spring 20 to separate from the outer shell 1 at 22 and thus break the circuit and extinguish the lamp.

Although I find it convenient to dispose of the oppositely electrically polarized elements of the lamp casing in air spaced relation as shown in Fig. 1, it is to be understood that they may be assembled in closer relation if separated by other dielectric. For instance, as shown in Figs. V and VI the lamp casing includes the metallic shells 25, 26 and 27 separated by insulating material 28 and 29; said shells 25 and 27 being similarly polarized in connection with the battery 30 and said shell 26 being oppositely polarized; so that when the shell 25 is punctured, as indicated in Fig. VI the shells 25 and 26 are electrically connected by contact with each other and if the casing is otherwise crushed or displaced the shell 27 comes in contact with the reflector shell 32 which, like the shell 5 above described, is connected with the opposite pole of said battery; so that, in either case, the lamp is short circuited and extinguished.

I do not desire to limit myself to the precise details of construction and arrangement herein set forth, as it is obvious that various modifications may be made therein without departing from the essential features of my invention as defined in the appended claims.

30 I claim:—

1. In a portable electric lighting apparatus, the combination with an electric generator; of an electric lamp in circuit therewith; a substantially hermetical lamp casing inclosing said lamp and having distinct crushable portions; and a spring pressed element whereby the lamp is extinguished when said casing is punctured or otherwise crushed, the lamp circuit being broken when one crushable portion is displaced, and short circuited when another crushable portion is displaced.

2. A miner's safety lamp casing, including an incandescent electric lamp socket and

having crushable portions, and a resilient element included in the electric circuit with said socket, automatically movable to break said circuit when one portion of the casing is displaced, and movable to short circuit said circuit when another portion of said casing is displaced.

3. A miner's safety lamp casing, including an electric lamp socket and having crushable portions, and an element included in the electric circuit with said socket, movable to break said circuit when one portion of the casing is displaced, and movable to short circuit said circuit when another portion of said casing is displaced.

4. A miner's safety lamp, including an outer casing and an inner casing; means normally maintaining said casings in insulated relation; a spring pressed element between said casings, normally electrically connected with the outer casing; and a crushable element normally insulating said spring pressed element from said inner casing; whereby when said crushable element is displaced, said spring pressed element is electrically connected with said inner casing to short circuit the lamp.

5. A miner's safety lamp, including an outer casing and an inner casing; means normally maintaining said casings in insulated relation; a spring pressed element between said casings; and a crushable element normally insulating said spring pressed element from said inner casing; whereby when said crushable element is displaced, said spring pressed element is electrically connected with said inner casing to short circuit the lamp.

In testimony whereof, I have hereunto signed my name at Philadelphia, Pennsylvania, this 28th day of February, 1913.

HIRAM HARRY HIRSCH.
